Inventor,
Hugh MacInnes,
By *N. J. Bernhard*
Attorney

UNITED STATES PATENT OFFICE.

HUGH MACINNES, OF JERSEY CITY, NEW JERSEY.

FLEXIBLE SHINGLE.

Application filed February 28, 1923. Serial No. 621,719.

This invention is a shingle for roofing and siding purposes, and more particularly, a shingle composed of flexible material.

The material is analogous to that ordinarily used in the art, being composed of a basic layer of felt, impregnated or saturated with a waterproofing agent, such as asphaltum, and provided on the weather surface with two coatings, one of which is composed of a relatively high melt point asphaltum to resist solar heat and the other consists of granular material incorporated with the surface coating.

The exposure of material of the foregoing character to solar heat and to the weather tends to distort the uncovered areas and margins of the shingle by curling upwardly the free unconfined ends of the shingles, thus displacing said margins relatively to the roof surface and permitting the entry of rain and wind.

The object of this invention is to interlock shingles in a manner to preclude such distortion of the free ends and margins of the flexible material composing the shingles, the effect of which is to retain the free ends and margins in a desired close relation to the surface and to exclude rain, snow and wind from entering below the shingles, keeping a tight roofing or siding.

The invention in a practical form is embodied in a strip shingle provided with a series of so-called tabs protruding from a margin of the strip and spaced relatively to each other by the formation in said margin of a series of re-entrant recesses or spaces, the salient feature of the invention being the provision of an aperture or slot at a definite point in the body of the shingle to the end that the tab of an overlying shingle will be received into said aperture or slot of an underlying shingle, and thereby lock said tab of an overlying shingle in fixed position with respect to the slot formed part of the underlying shingle, in a manner to retain the free ends and margins exposed to the weather from distortion and displacement, and to thus exclude wind, rain and snow from entering below such exposed edges and ends of the shingles.

Other functions and advantages of the invention will appear from the following description taken in connection with the drawings, wherein—

Figure 1 is a view of a plurality of shin-

gles in strip form applied in locked relation to each other as embodied in my invention.

Figure 2 is a detail plan view of part of a shingle strip embodying the article of my invention.

Figure 3 is a cross section on the line 3—3 of Figure 2.

As shown in the drawings, the invention is embodied, in one practical form, as a continuous strip A, one margin *a* of which is straight and unbroken, whereas the other margin is of such formation as to produce a succession of tabs, B, formed by a series of re-entrant recesses *b*, the form and dimensions of which recesses correspond to the shape and sizes of the tabs of a complementary strip cut in a reversed position from the shingle strip A.

Obviously, the number of tabs B, and the form and dimensions thereof, on the strip A may be varied as desired, but it is preferred to provide tabs of tapering formation, each having a straight lower edge, *c*, and side edges, *c'*, inclined to the straight lower edge *c*. By cutting a complementary strip from the material, and reversing the complementary strip to the position of strip A, there results in the strip A a series of recesses bounded by the lines *c'* and *c*; the latter lines *c* being parallel to the longitudinal axis of strip A and parallel also to edges *c'* at the free ends of tabs B.

An essential feature of the invention is the provision of apertures D in the shingle and in a definite relation to the serrated margin thereof, which serrated margin is constituted by the presence of tabs B. Each aperture is cut out of the body of the shingle, and in the strip shingle shown, a succession of said apertures is produced in the body of the shingle strip. Each aperture is represented as a slot, formed in the shingle material adjacent the boundary edge *c* and parallel therewith, the length of said slot exceeding the width of the tab at the free extremity thereof, and the width of said slot D being sufficient for the easy and free insertion thereinto of a tab on the overlying shingle, it being noted that the slot D exceeds in length the boundary edge *c* adjacent thereto.

The strip shingles are assembled by laying them one over the other upon a roof or against the side of a structure, and in such manner as to conceal the straight margins

of the strips, and for the protruding tabs of one strip to lie over the recesses in the serrated edge of the underlying strip, the tabs of the overlying and underlying stripslapping at their margins, as shown in Figure 1. In thus assembling the strips the free ends of the tabs B of an overlying strip are bent or deflected slightly and inserted into the slots D of an underlying strip, the deflection and insertion of the tabs being more fully depicted at b in Figure 3, and also indicated in Figure 1. The tabs B of the strips are of such form and assembled in such manner as to impart to the surface of the roof the appearance of hexagonal individual shingles, see Figure 1. Obviously, the strips are mechanically fastened in a desirable way, as by nailing them in position, but while the tabs are not thus mechanically fastened, the insertion of the free ends of said tabs into the slots produces means by which said otherwise unattached tabs are locked or retained securely with a view to overcoming that tendency of the composite material to curl upwardly under the effects of solar heat and the weather, whereby the tabs are retained in close relation to the surface of a roof or siding and thus preclude the entry of rain or snow, as well as to prevent the tabs from being lifted out of position by the pressure of the wind.

My invention is herein shown and described as embodied in strip form, and while this is a preferred form, it is not desired to restrict the invention to strips for the reason that it may be also embodied in the form of individual or separate shingles, adapted for assemblage to effect a desired locking engagement for the free ends of the overlying shingles with slots in underlying shingles. Such construction and arrangement may obviously be made by those skilled in the art, and, accordingly, it is unnecessary to illustrate or further describe the same.

Having thus fully described the invention, what I claim as new and desire to secure by Letters Patent is:

1. Shingles in strip form comprising a body portion having on one margin a plurality of tabs and provided in the body por-

tion with a plurality of slots each occupying a definite relation to the interval between two adjacent tabs, the shingles being assembled for the free ends of overlying tabs to enter the slot in the body of an underlying shingle strip.

2. Strip shingles embodying a body portion having on one margin thereof a plurality of tabs and provided on said body portion with slots extending lengthwise of the body portion and each slot occupying a definite relation to the interval separating two adjacent tabs, the length of said slot being in excess of the width of the tab at the free end thereof.

3. Shingles provided with alternating recessed and lapping portions, said shingles having slots extending parallel to the outer ends of said lapping portions and with said outer ends of overlapping shingles retained within the slots of underlying shingles.

4. Shingles assembled to produce alternating recessed and lapping portions, said shingles being provided in a definite relation to the recessed portions with slots extending parallel with the outer ends of the lapping portions, and with said outer ends of the overlying shingles inserted into the slots of underlying shingles.

5. A strip shingle provided on a margin thereof with alternating tabs and recesses, said shingle having in its body portion a plurality of slots positioned adjacent to the inner termini of said recesses and said slots extending in a direction parallel with the outer ends of said tabs.

6. A strip shingle provided on the margin of the body portion with alternating recesses and tabs, the outer ends of said tabs being bounded by straight edges, and said shingle having in the body portion thereof a succession of slots positioned adjacent to the recesses, each slot extending lengthwise of the shingle body and adapted to receive the straight end edge portion of an overlying tab.

In testimony whereof I have hereunto signed my name this 10th day of February, 1923.

HUGH MACINNIES.
